ATTORNEY

UNITED STATES PATENT OFFICE.

DOROTHY MILLER, OF KANSAS CITY, MISSOURI.

MUSICAL-GAME APPARATUS.

1,325,104.

Specification of Letters Patent. Patented Dec. 16, 1919.

Application filed November 14, 1918. Serial No. 262,475.

To all whom it may concern:

Be it known that I, DOROTHY MILLER, a citizen of the United States, residing at Kansas City, in the county of Jackson and State of Missouri, have invented certain new and useful Improvements in Musical-Game Apparatus, of which the following is a specification.

This invention relates to musical games and more especially to key-board games, and my object is to produce apparatus constituting a game whereby one may learn the names and locations of notes on the treble and bass clefs and on the keys on the key-board of a piano entertainingly and subconsciously. A further object is to provide a competitive game of the character set forth for the purpose of stimulating the interest and concentration and therefore quickening and strengthening the memorizing and reasoning faculties of the players.

With these objects in view the invention consists in certain novel and useful features of construction and organization of parts as hereinafter described and claimed; and in order that the invention may be fully understood reference is to be had to the accompanying drawing, in which:

Figure 1, is a plan view of a key-board game apparatus embodying the invention.

Fig. 2, is a cross section on the line II—II of the same.

In the said drawing a board 1, preferably rectangular in form and constituting a field, is inclosed by marginal strips forming a wall 2, on the upper surface of one side of which is represented a piano key-board 3, only one being shown, and said wall is provided with pockets 4 for the keys of the key-board, the preferred construction being to produce a pocket in each key.

On the field is represented a treble clef 5, and a bass clef 6, the treble clef staff being supplemented by one added line below, and the lines and spaces of the staffs may contain the proper identifying marks or letters (not shown), to serve as guides in the placement on the staffs of correspondingly lettered marbles 7.

The board is placed upon a small table 8, and the game is preferably played by no more than four players seated at the table

around the board, and each player will be provided with a shooter marble or taw 8 to be shot or rolled by the player in the attempt to displace the lettered marbles from the staffs. 55

Upon starting the game one of the players will shoot or roll his shooter marble or taw on the field in the attempt to knock or displace a lettered marble from its staff. If he succeeds he picks up the displaced marble and upon observing its letter, or, if it is unlettered, the position from which it was driven, announces that it represents a certain note and that such note is located at a certain place on the key-board, mentioning the place with respect to the black keys thereof, as I have found that the locating of the keys in the minds of children is greatly expedited by utilizing the groups of two black keys and three black keys as a basis for the identification by name and location of the white keys. If the player fails in his attempt to displace a lettered marble from 75 a staff or to properly call and locate said marble in the corresponding pocket of the key-board, he loses his turn at play and another player takes his turn, and when he fails the next player, etc., until all of the 80 field marbles have been displaced and properly stationed on the key-board. In practice it is preferable that there shall be a key-board for each player so that the result of the play shall appear at a glance. Of course, the result of the play may be noted upon a tab, but this method of keeping score is not desirable or altogether practicable where small children are the players. 85

In teaching the game to children I have 90 found that it is advisable to require them to announce the location on the key-board of a displaced marble by referring to either the groups of two black keys or the groups of three black keys, for example, if the displaced marble represents a C, the player will announce that C is the first white key to the left of the two black keys. I have also found it advantageous to have the players play on the C marbles first so that they 95 shall by repetition learn where the C's occur on the treble and bass clefs, and then take up the letters of the other keys, learning the location of the white keys C, D and E with 100

respect to the group of two black keys, and then learning the location of the white keys F, G, A and B with respect to the group of three black keys. The game not only teaches 5 the location of the white keys with respect to the black keys but also teaches where the corresponding keys are in the treble and bass staffs.

To illustrate more clearly the location of 10 the white keys with respect to the two groups of black keys, it will be learned that C and E are respectively to the left and right of the group of two black keys and that D is between said two black keys, and that the 15 key F is to the left of the three black keys, and that the key D is to the right of the three black keys, that the key G is the lower white key, and that the key A is the upper white key within the group of three black 20 keys, said keys being termed lower and upper respectively because of their difference in tone or pitch.

The game is very entertaining to children 25 because it is a competitive game and a child quickly learns the location of the keys on the staff and on the key-board.

By means of this game one can readily learn the location of any note upon the bass staff with respect to the middle C on the 30 key-board, for example, when the marble representing A on the bass staff is displaced, the player is required to state that A is the first bass space and is the second A below middle C on the key-board; that C is the 35 second bass space and the first C below middle C on the key-board; that E is the third bass space and the first E below middle C on the key-board; that G is the fourth bass space and the first G below middle C on the 40 key-board. The location of the lines with respect to the key-board is learned in a similar manner. In winning the game of spaces or lines, the board may have to be cleared a number of times, as the first one who succeeds 45 in collecting and properly locating the marbles F, A, C, E, or E, G, B, D and F wins the game.

From the above description it will be seen that I have produced a device of the 50 character described which possesses all of the features of advantage enumerated as desirable, and while I have illustrated and described the preferred form of the invention it is to be understood that I reserve the 55 right to make all changes properly falling within the principle of construction in-

volved and the spirit and scope of the appended claims.

I claim:

1. A musical game apparatus, comprising 60 a field containing one or more musical staves, inclosed by a wall, objects to be positioned on the lines and spaces of the staff or staves, taws to be shot or rolled on the field for effecting the displacement of said objects 65 from the staff or staves, and a representation of a piano key-board, the displaced objects representative of particular notes, being adapted to be placed on the corresponding keys of said key-board. 70

2. A musical game apparatus, comprising a field containing one or more staves and inclosed by a wall, objects to be positioned on the lines and spaces of the staff or staves and bearing characters of identification corresponding to the respective lines and spaces of said staff or staves, taws to be shot or rolled in the field for effecting the displacement of said objects from the staff or staves, and a representation of a piano key-board, 75 the displaced objects representative of particular notes being adapted to be placed on the corresponding keys of said key-board. 80

3. A musical game apparatus, comprising a field containing one or more staves and 85 inclosed by a wall, objects to be positioned on the lines and spaces of the staff or staves, taws to be shot or rolled on the field for effecting the displacement of said objects from the staff or staves, and a representation of a 90 piano key-board, provided with a pocket for each key for the reception respectively of objects displaced from corresponding lines or spaces of the staff or staves by the shooting or rolling of a taw or taws. 95

4. A musical game apparatus, comprising a field containing one or more staves and inclosed by a wall, objects to be positioned on the lines and spaces of the staff or staves, and bearing characters of identification corresponding to the respective lines and spaces of said staff or staves, taws to be shot or rolled on the field for effecting the displacement of said objects from the staff or staves, and a representation of a piano key-board 100 provided with a pocket for each key for the reception respectively of objects displaced from corresponding lines or spaces of the staff or staves, by the shooting or rolling of a taw. 105

In testimony whereof I affix my signature.
DOROTHY MILLER.
